HEAT EXCHANGER

Sigmund Kopp, Glen Rock, N. J., assignor to
 American Locomotive Company, New York,
 N. Y., a corporation of New York

Application March 16, 1944, Serial No. 526,682

1 Claim. (Cl. 257—224)

1

This invention relates to heat exchangers and more particularly to means for preventing extreme temperatures in the tube sheets, or other parts, of the exchanger.

In certain types of heat exchangers the tube sheets, or other parts thereof, may be exposed to extreme temperatures, either extremely high or extremely low. In designing such an exchanger, means should be provided for moderating these extreme temperatures. For instance, in a heat exchanger adapted for heat exchange between hot fluid-catalyst mixture and cold oil, wherein the hot fluid passes through tubes, it will be found that the tube sheets for the tubes will be subjected to extremely high temperatures due to the fluid-catalyst mixture. This high tube sheet temperature, if not counteracted, will result in distortion of the tube sheets and injury thereto.

It is known that distortion of heat exchanger parts, due to extreme temperatures, may be avoided by the choice of metals. For instance, nickel alloy steels may be employed where low temperatures are encountered and chrome and chrome-molybdenum steels may be employed where high temperatures are encountered. However, where such metals are not available, or the cost is prohibitive, other means must be sought so that relatively inexpensive and available metals may be used and protected to withstand the aforesaid extreme temperatures. Thus, where low carbon steel is employed, injury from extreme temperatures may be minimized or avoided by proper insulation of the endangered parts, or means may be provided to cool hot surfaces, or heat cold surfaces, as the case may be.

The present invention is directed toward providing means for cooling extremely hot surfaces, or heating extremely cold surfaces, of parts of a heat exchanger exposed to extreme temperatures, to the end that a cheap and plentiful metal such as low carbon steel, may be employed in the manufacture of these parts. The invention is not confined, however, to means for so heating or cooling any particular kind of metal as the means, obviously, can be so employed with various kinds of metals, wherever the need arises.

An object of the present invention is to provide a heat exchanger having means for cooling surfaces of parts thereof exposed to extremely high temperatures, or for heating surfaces or parts thereof exposed to extremely low temperatures.

Other and further objects of this invention will appear from the following description, the

accompanying drawings and the appended claim.

Referring to the drawings forming a part of this application, Figure 1 is a foreshortened vertical central section of a heat exchanger embodying the present invention, parts being shown in full; Fig. 2 is a section on the line II—II of Fig. 1, the tubes being indicated by circles; Fig. 3 is a foreshortened section on the line III—III of Fig. 4, showing another embodiment of the invention, parts being shown in full and parts being omitted; Fig. 4 is a section on the line IV—IV of Fig. 3, parts being broken away, some only of the tubes being shown and indicated by circles; Fig. 5 is a section on the line V—V of Fig. 3, parts being broken away, some only of the tubes being shown and indicated by circles; Fig. 6 is a section on the line VI—VI of Fig. 3, some only of the tubes being shown and indicated by circles; and Figs. 7 and 8 show a further embodiment of the invention, Fig. 7 being a view similar to Fig. 5 and Fig. 8 being a section on the line VIII—VIII of Fig. 7, showing a portion of the structure of Fig. 7.

25 The heat exchangers shown in the drawings are types suitable to effect heat exchange between a hot fluid, such as a flue gas catalyst mixture, flowing through the tubes, and a cold fluid, such as cold oil, flowing through the shell, where-

30 in the tube sheets are exposed to extreme heat from the fluid-catalyst mixture. While the heat exchangers are adapted for other types of heat exchange, and while the invention is applicable to other types of heat exchangers, the following

35 description will be of the heat exchangers shown when employed with the hot fluid-catalyst mixture in the tubes and the cold oil in the shell, it being believed that the invention will be clearly understood from such a description.

40 Referring to Figs. 1-2 of the drawings, a heat exchanger, indicated generally by the reference numeral 1, embodying the present invention, is shown therein. Assuming for the purposes of description, that it is vertically disposed, as

45 shown, it includes a top tube sheet 2, a bottom tube sheet 3, a shell 4 spanning and welded to the tube sheets, a top header or cap 5 bolted to the sheet 2 and provided with an outlet nozzle 6, and a bottom header or cap 7 bolted to the sheet 3 and provided with an inlet nozzle 8. Gaskets are provided between the tube sheets and caps in the usual manner. A plurality of tubes 9 extend between and have their ends secured in orifices in the tube sheets and open into the

50 interior of the caps. The tubes are preferably

55

staggered so that the fluid flowing thereacross must flow in a circuitous path between the tubes, no straight-through path in the direction of flow between the tubes being provided.

The shell contains a plurality of staggered horizontal baffles 10, provided with orifices for the tubes and secured to the shell for causing shell fluid to flow through the shell crosswise of the tubes in a circuitous passage. An inlet nozzle 11 opens into the shell at the top a short distance below the tube sheet 2 and an outlet nozzle 12 opens from the shell at the bottom a short distance above the tube sheet 3.

It is contemplated that the shell fluid and the tube fluid will be in counterflow. For instance, hot fluid (fluid-catalyst mixture) may enter the cap 1 through the nozzle 8 from a suitable source of supply, such as a fluid-catalyst mixture separator, flow upwardly through the tubes 9 into the cap 5 and leave the exchanger through the nozzle 6 which may be connected to a fluid-catalyst mixture regenerator. Cooler fluid (oil) may enter the shell through the nozzle 11 and leave the shell through the nozzle 12 after flowing through the shell crosswise of the tubes in a circuitous passage downward. The flows through the tubes and shell are indicated in the drawings by arrows.

The tube walls will be heated by the hot fluid passing through the tubes and the maximum temperatures that they reach will depend upon the magnitude of the heat transfer rates from the fluid-catalyst mixture to the tube wall on the tube side and to the oil or cold fluid from the tube wall on the shell side. By correctly proportioning the size of the tubes and shell, the number of tubes employed, the shell cross-sectional area closed off by each of the baffles 10 and the distance between the baffles 10, these maximum tube temperatures may be held within permissible limits.

The temperature of the shell wall will be lower than the tubes, as the shell is filled with a lower temperature fluid than the tubes. This temperature may similarly be controlled to some extent by the same proportioning mentioned in regard to controlling the temperature of the tubes. Moreover, if desired, the outer face of the shell, or any desired portion thereof, may be insulated (not shown) in any well-known manner to prevent loss of heat through the shell wall.

Furthermore, the tube sheets 2 and 3, which are of relatively thick metal compared with other parts of the exchanger, are subjected to extreme heat as they are in contact with the hot fluid in the caps 5 and 7 respectively, and further receive heat from the tubes which are secured in the tube sheets. It is therefore desirable to provide means to limit the maximum temperatures of the tube sheets.

The means employed to partially cool the tube sheet 2 is a baffle 13 shown in Figs. 1 and 2. This baffle 13 includes a thin horizontal plate 14, provided with orifices for the tubes, spaced a short distance below tube sheet 2 and having a straight edge 15 extending across the shell and leaving a portion of the shell at one side unbaffled. At the other side the plate 14 has a curved edge 16 spaced from and concentric to the adjacent wall portion of the shell. The plate 14, at its remaining sides, may be welded to the shell. A curved vertical plate 17 is welded to the plate 14 at the edge 16 and extends downwardly slightly below the nozzle 11 and is connected to the shell at its vertical edges by walls 17". Walls 17" and plate

17 are connected at their bottom edges to the shell, by a curved horizontal plate 18.

A similar baffle 13' is provided adjacent tube sheet 3 and similar parts thereof are designated by similar reference numerals with an accent added, no further description of same being deemed necessary.

A plurality of seal strips or fins 19, extending between the plate 14 and the tube sheet 2, are welded to the plate 14 and to the adjacent face of the shell. The arrangement of the fins 19 is best shown in Fig. 2. These fins provide a stagnant area for shell fluid adjacent the tube sheet and serve to limit the net free flow area for shell fluid over the plate 14, preventing flow of shell fluid around the bundle of tubes and forcing the flow to be between the tubes. Similar fins may be employed for a similar purpose with the baffles 10 and 13', if desired.

Baffles 13 and 13' provide means, as aforesaid, for partially cooling the tube sheets. This is accomplished by regulating the flow area of shell fluid and consequently the heat transfer rate of cooling shell fluid to the tube sheets so as to cool them more than would be the case if the baffles 13 and 13' were not provided. This is accomplished by forcing the shell fluid to wash over the tube sheets for cooling same. The distance between baffle 13 and tube sheet 2, or between baffle 13' and tube sheet 3, will be chosen so as to provide the desired heat transfer rate between the shell fluid and the tube sheets 2 and 3.

The embodiment of Figs. 1 and 2 illustrates the present invention applied in a simple type of heat exchanger. The embodiments of Figs. 3 to 6 and of Figs. 7 and 8 show the invention applied in more complex types of heat exchangers with additional means provided.

The heat exchanger of the embodiment of Figs. 3 to 6 is indicated generally by the reference numeral 20. It has a hollow base 21 providing a header or chamber 22 and a top flange 23. Chamber 22 is insulated with refractory brick or other means 24 and may be connected to a source of heat, as to a fluid-catalyst mixture separator. A tube sheet 25 is mounted on top of the flange 23. The exchanger further has a composite outer shell 26, formed of a flanged bottom shell portion 27 mounted on top of the tube sheet 25, a flanged intermediate shell portion 28 mounted on top of portion 27, and a flanged top shell portion 29 mounted on top of portion 28. Gaskets 30 are provided between the various engaging parts of the base 21, tube sheet 25 and shell portions 27, 28 and 29, and these parts are secured together by bolts 31.

An inner shell 32 is mounted on tube sheet 25 within shell 26. It provides, with shell 26, an annular space 33 therebetween. Shell 32 has a sliding fit at its upper end with an angle bracket 34 secured to a top tube sheet 35, which tube sheet is disposed in shell portion 29 in slightly spaced relation with the inner face thereof. A ring 36 is secured to the top face of the tube sheet 35 by tap bolts 37, a gasket being provided therebetween. A channel or header 38 extends upwardly from and is secured to the ring 36. It may be connected to a chimney, similar to nozzle 6 of Fig. 1. Ring 36 is secured to shell portion 29 by an annular expansion joint flexible collar 39 welded to the ring 36 and to the portion 29. Collar 39 has an inside diameter at least as large as the inside diameter of the outer shell. Orifices 40 formed in portion 29 afford communication between space 33 and the interior of collar 39 so as

to equalize temperature and pressure therebetween. Shell 32 is shown made as an integral cylinder. However, it may be made of several vertical and/or horizontal sections secured together if desired.

Tubes 41 are disposed in shell 32 with their ends secured in orifices in the tube sheets. The tubes are staggered so that fluid flowing across the shell must flow in a circuitous path between the tubes, no straight-through path in the direction of flow between rows of tubes being provided, as will presently more fully appear. Horizontal baffles 42, having orifices for the tubes, and being staggered, divide the shell 32 so that the flow therethrough is substantially horizontally across the tubes in a circuitous path downward through the shell. Each baffle closes off the greater portion of the cross-sectional area of the shell. Tie rods and spacers 43 support the baffles.

A flange 44 is secured at its outer edge to the top flange of shell portion 27 and at its inner edge to shell 32, thereby dividing space 33 into a lower chamber 45 and an upper chamber or space 45'. Shell 32 is strengthened by annular rings 46 secured to the outer face of shell 32.

A shell fluid inlet nozzle 47 opens through shell portion 28 near the top thereof into the space 45', and a shell fluid outlet nozzle 48 opens through the shell portion 27 from the chamber 45.

It is contemplated that the shell fluid and the tube fluid shall be in counterflow as was the case in exchanger 1. Therefore hot tube fluid enters the tubes from chamber 22 and leaves the tubes, passing into channel 38. Thus the tube sheets would be subjected to extremely high temperatures if they were not protected, as will later more fully appear. The tubes are protected against excessive temperatures in the same manner as the tubes of exchanger 1 were protected and no further description thereof is deemed necessary. Chamber 45 and space 45' below nozzle 47 each holds a relatively stagnant body of shell fluid which to some extent insulates the shell 32 and prevents rapid heat transfer therethrough. The outside of the exchanger 20 may be insulated, if desired, similarly to exchanger 1.

Shell fluid of a lower temperature than the tube fluid enters space 45' through the nozzle 47. Space 45' below nozzle 47 contains a trapped volume of shell fluid as aforescribed. Shell fluid directly above nozzle 47 is continually passing into shell 32 through an opening 49. Some shell fluid also passes through the clearances between the tube sheet 35, ring 36 and shell portion 29, and through the orifices 40 into collar 39, providing a substantially stagnant volume of shell fluid in the collar 39. The shell fluid passing through the shell 32 flows crosswise of the tubes in a circuitous route as indicated by the arrows. It leaves the shell 32 through an opening 50 communicating with chamber 45.

Special means are provided to protect the tube sheets, as was the case in the exchanger 1. It will be seen from Fig. 3 and Fig. 4 that a plate 51, orificed for receiving the tubes 41 and spaced a short distance below tube sheet 35, closes off the upper portion of shell 32 except for a small portion, thereby providing an opening 52. A vertical baffle 53 extends from the inner face of the shell 32 to substantially the center thereof, and forms a partition between the plate 51 and tube sheet 35. Opening 49 is to the rear of the baffle 53 (see Fig. 3) and opening 52 is at the opposite (front) side of the baffle (see Fig. 4). Shell fluid passing from space 45' through opening 49 into the space

above the plate 51 fills this space and must flow crosswise of the tubes over the bottom face of the tube sheet 35, passing around the free end of baffle 53 whereupon it flows back on the other side of the baffle 53 to the opening 52 through which it flows into the space above the uppermost baffle 42. This flow of relatively cool shell fluid over tube sheet 35 acts to cool the tube sheet 35 more than would be the case were this plate 51 not employed.

The means for protecting the tube sheet 25 is somewhat different than the means for protecting the tube sheet 35 and includes, besides the cooling feature, means for supporting the tube sheet 25 to prevent bowing due to weight superimposed thereon, such as the weight of the inner shell, the tubes, the upper tube sheet, the channel 38, and the fluid in the inner shell. This support is more fully described in a copending application of George B. Farkas, Serial No. 526,683, filed March 16, 1944, and reference may be had thereto, if desired, for a more complete understanding of the structure of the support. Shell 32, below nozzle 48, is partitioned into quarters by vertical walls 54 and 55 disposed at right angles to each other and meeting at the center of the shell, wall 55 being made in two pieces 55a and 55b. The portions of wall 54 on opposite sides of the wall 55 are indicated by the numerals 54a and 54b.

A horizontal wall 56 is disposed on top of walls 54 and 55, and a four-piece horizontal wall 57 is disposed between wall 56 and tube sheet 25, each quarter of wall 57 being disposed between adjacent portions of walls 54 and 55 and welded thereto. Walls 54 and 55 are each formed of two spaced plates, as is clearly shown in Fig. 6, and the plates of each part of wall 55 are welded to the plates of wall 54.

Walls 56 and 57 have openings 58 and 59 respectively similar to opening 52, opening 58 being on one side of wall 54 and opening 59 being on the other side of wall 54 and vertically aligned with opening 52. Wall 56 also has orifices in line with the spaces between the plates of walls 54 and 55, and stud bolts 60 secure the supporting means to the tube sheet 25, thereby stiffening same against bending due to the aforesaid superimposed load.

The wall 54 prevents the use of tubes 41 in line therewith, and this omission of tubes 41 would provide a clear way across the shell for flow of shell fluid without impingement on any tubes, resulting in a loss of heat exchange efficiency. Therefore dummy tubes 61, extending through orifices in the baffles 42 and being plugged at both ends, are employed above wall 54, these tubes 61 at their upper ends extending through, and being secured in, the top plate 51 and terminating flush with the upper surface thereof.

The supporting means, together with the adjacent portion of the inner shell and the tube sheet 25, form eight intercommunicating compartments, there being four compartments 62 between the walls 56 and 57, and four compartments 63 between the wall 57 and tube sheet 25. Shell fluid enters the first compartment 62 through opening 58, and then flows counterclockwise in succession through the remaining three compartments 62, openings 64 being provided in the wall part 55a, portion 54a and part 55b between walls 56 and 57 for this purpose. Shell fluid passes from the last compartment 62 to the first compartment 63 through the opening 59, and then flows clockwise in succession through the remaining three compartments 63, openings 65

being provided in the wall part 55b, portion 58a and part 55a between wall 57 and tube sheet 25 for this purpose. Shell fluid flows from the last compartment 63 through the opening 50 therein into the chamber 45 and therefrom to the nozzle 48.

Wall 57 performs the same function as plate 14' of exchanger 1, that is to say, it causes the shell fluid to wash over the tube sheet 25, cooling same. Thus the remarks made in relation to plate 14' apply equally as well to the wall 57.

It will be apparent from the foregoing description that tube sheets 25 and 35 have been relieved of extreme service stresses, this being partly a result of the cooling action of the shell fluid washing over the tube sheets and partly a result of the freedom for expansion and contraction of the tubes and tube sheets due to the employment of the flexible collar 39. Therefore the tube sheets can be made thinner than would otherwise be the case, this thinness further assisting in the cooling of the tube sheets and the relieving of stresses therein. The supporting means provided for the tube sheet 25 makes the use of a thin tube sheet at this location permissible.

In both exchangers 1 and 20 the shell fluid flows in a circuitous path lengthwise of the shell, and in a simultaneous circuitous path crosswise of the tubes.

A modified form of supporting means embodying the present invention is shown in Figs. 7 and 8. In the main, it is similar to the supporting means of exchanger 20, and therefore only the differences thereover will be described, and like parts will be designated by like reference numerals with an accent added. The supporting means of Figs. 7 and 8 is similar to that shown in the aforementioned copending application of George B. Farkas, and reference may be had to this copending application for a more complete description thereof.

Referring to Fig. 7, it will be seen that the portion of the inner shell 32' adjacent the supporting means is made in four flanged parts 66, the flanges 67 being bolted to the plates of walls 54' and 55', which extend substantially to the outer shell 26'. Filler pieces 68 are employed between the plates of walls 54' and 55' adjacent the flanges 67.

The walls 54' and 55' are undercut so that they rest on the tube sheet 25' only at their extremities, which are designated as feet 69. As these feet are directly over base 21', the supporting means acts as a bridge from which tube sheet 25' is suspended, the entire weight superimposed on the tube sheet 25' being transmitted to the base 21' vertically in line therewith so that the strongest resistance to this weight is provided.

The feet are reinforced by webs 70. A horizontal wall 71 is provided in the chamber 45' and an opening 72 is formed therein to permit flow of shell fluid to nozzle 48'.

The flows of tube fluid and shell fluid through the exchanger of Figs. 7-8 are similar to the flows through the exchanger of Figs. 3-6 and no further description thereof is deemed necessary. As the walls 54' and 55' are undercut as aforesaid, there will be some short-cutting of shell fluid between the compartments adjacent tube sheet 25' but this undercutting will not be sufficient to materially affect the orderly flow of shell fluid through the compartments adjacent tube sheet 25' in the intended manner.

While there have been hereinbefore described approved embodiments of this invention, it will be understood that many and various changes and modifications in form, arrangement of parts and details of construction thereof may be made without departing from the spirit of the invention and that all such changes and modifications as fall within the scope of the appended claim are contemplated as a part of this invention.

The invention claimed and desired to be secured by Letters Patent is:

A vertical heat exchanger comprising a shell; a horizontal tube sheet closing one end of said shell; tubes in said shell secured in said tube sheet; a header secured to said tube sheet at the side thereof remote from said tubes; and a device for minimizing the extent that the temperature in said header affects the temperature of said tube sheet including two vertical walls crossing at right angles to each other in said shell and engaging said tube sheet and shell wall, providing four compartments, said shell having a port opening to one of said compartments, said device further having a horizontal wall parallel to and adjacent and spaced from said tube sheet and engaging said vertical walls and shell wall, said horizontal wall having a port opening another of said compartments to said shell, said other compartment being adjacent said one compartment, one of said vertical walls having a port opening said other compartment to a third compartment adjacent thereto, the other of said vertical walls having a port opening said third compartment to the fourth compartment, and said one of said vertical walls having another port opening said fourth compartment to said one compartment for a circular series flow between said shell and horizontal wall ports whereby shell fluid washes over the entire adjacent surface of said tube sheet, thereby effecting said temperature minimizing of said tube sheet.

SIGMUND KOPP.
